CLAIM

The ornamental design for a golf club brush as shown and described.

DESCRIPTION

FIG. 1 is a perspective view of a golf club brush, showing my new design;

FIG. 2 is a front elevation view of the golf club brush in FIG. 1;

FIG. 3 is a rear elevation view of the golf club brush of FIG. 1;

FIG. 4 is a left-side elevation view of the golf club brush of FIG. 1;

FIG. 5 is a right-side elevation view of the golf club brush of FIG. 1;

FIG. 6 is a top view of the golf club brush of FIG. 1; and,
FIG. 7 is a bottom plan view of the golf club brush of FIG. 1.

In the drawings, the broken lines illustrate portions of the article and form no part of the claimed design.

1 Claim, 7 Drawing Sheets
